CLAIM

The ornamental design for container, especially for
transporting skis on the roof of a car, substantially as
shown and described.

DESCRIPTION

FIG. 1 is a top front perspective view of a container
especially for transporting skis on the roof of a car
showing our new design;

FIG. 2 is a bottom rear perspective view thereof; and
FIG. 3 is a side-elevational view thereof, the opposite
side being a mirror image of the side shown.

FIG. I.

FIG. 2.

FIG. 3.
